Laura Mood Schneider, Los Angeles, Calif.

Application November 18, 1949, Serial No. 6,136

Term of patent 7 years

(Cl. D45—19)

To all whom it may concern:

Be it known that I, Laura Mood Schneider, a citizen of the United States of America, residing at Los Angeles, county of Los Angeles, and State of California, have invented a new, original, and ornamental Design for a Pin, of which the following is a specification, reference being had to the accompanying drawing, forming part thereof.

Fig. 1 is a front elevational view of a pin showing my new design; and

Fig. 2 is a side elevational view thereof.

I claim:

The ornamental design for a pin, as shown.
LAURA MOOD SCHNEIDER.
